UNITED STATES PATENT OFFICE.

GRAEFF MILLER, OF RIDGEWOOD, NEW JERSEY.

DESIGN FOR A BOTTLE OR SIMILAR ARTICLE.

Application filed December 11, 1925. Serial No. 15,710. Term of patent 14 years.

To all whom it may concern:

Be it known that I, GRAEFF MILLER, a citizen of the United States, and a resident of Ridgewood, county of Bergen, State of New Jersey, have invented a new, original, and ornamental Design for a Bottle or Similar Article, of which the following is a specification, reference being had to the accompanying drawing, forming a part thereof.

In the drawing:

Fig. 1 is a view in side elevation of a bottle provided with surface decorations and having a metal cap closure; and

Fig. 2 is a view in end elevation of the bottle shown in Fig. 1.

The body portion of the bottle is of a frosted appearance with raised curved ribs contrasting with the frosted portion.

I claim:

The ornamental design for a bottle or similar article, substantially as shown and described.

GRAEFF MILLER.
